Attorney

UNITED STATES PATENT OFFICE

CONSTANTINO CARPENTIERI, OF NEW HAVEN, CONNECTICUT

ARCH SUPPORTING HEEL

Application filed September 14, 1931. Serial No. 562,793.

This invention relates to improvements in rubber heels for shoes and has particular reference to an arch supporting heel.

The primary object of the invention resides in a rubber heel having an extension which is adapted to underlie the arch of the shoe when applied thereto, to correct faulty leg structure such as the relief of tiredness, knee pains, and weak and imperfect arches.

Another object of the invention is to provide an extension arch support which forms part of a rubber heel, whereby the same may be secured in position simultaneously with the heel.

A further object of the invention is the provision of an arch supporting rubber heel which is simple of construction, inexpensive of manufacture, and easy to apply to position upon a shoe.

With these and other objects in view, the invention resides in the certain novel construction, combination and arrangement of parts, the essential features of which are hereinafter fully described, are particularly pointed out in the appended claim, and are illustrated in the accompanying drawing, in which:

Figure 1 is a side elevational view of a shoe with my improved heel in position thereon,

Figure 2 is a bottom plan view of the same, and;

Figure 3 is a perspective view of a slightly modified form of heel.

Referring to the drawing by reference characters, the numeral 10 designates a resilient rubber heel body of a shape to conform to the heel end of a shoe 11 and which is of a thickness to provide the desired lift without the aid of additional layers or thicknesses of leather. In other words the heel is connected directly to the outer sole as best seen in Fig. 1 of the drawing.

Formed integral with the heel body 10 is an arch supporting extension or member 12 which in figures 1 and 2 includes a forwardly extending portion 13 and a substantially right angular extending portion 14, the portion 14 extending in a direction to

underlie the inner side of the arch 15 of the shoe 11. The extension member 12 is of the same thickness as the heel body 10 so that the tread portion of the arch supporting extension is on the same plane as the tread portion of the heel body. Both the heel body and the arch extension is provided with spaced openings 16 for the passage of securing elements in the form of nails by which the heel may be fixedly connected to the shoe 11. In Fig. 2 of the drawing, the shoe for the right foot has been shown and it will be noted that the angular extension portion 14 extends toward the inner side of the shoe so as to support the arch at its highest or weakest point, thus it will be necessary to construct the heels in pairs, one for the left shoe and the other for the right shoe in order that the portions 14 of the respective heel extend inwardly.

In Fig. 3 of the drawing, a construction similar to that shown in Figures 1 and 2 is disclosed with the exception that the angular extending portion 14' is disposed at different angles than the portion 14, that is it extends outwardly and inwardly. The rest of the construction in this form is identical with that shown and described in the preferred form.

From the foregoing description, it will be seen that I have provided a rubber heel structure which has an arch supporting member integral therewith which is brought to bear against the weakest portion or area of the arch and which member is resilient to absorb any shock which may be imparted during walking. Although I have specifically stated that the thickness of the arch extension is substantially the same as the thickness of the heel body, it will be understood that the same may be varied to best suit each individual wearer.

While I have shown and described what I deem to be the most desirable embodiment of my invention, I wish it to be understood that various changes as come within the scope of the appended claim may be resorted to if desired.

Having thus described the invention, what is claimed as new and what it is desired to

secure by Letters Patent of the United States, is;

A rubber heel comprising a body portion of the same area as the heel portion of a sole of a shoe and adapted to be connected to said heel portion and a forwardly extending extension of narrow cross sectional shape and of the same thickness as the body portion, said extension being formed integrally with the forward edge of the body portion and connected to the central part of the front edge thereof and adapted to be connected to the shank portion of the sole, and a single projection formed on the front portion of the extension at one side thereof and extending to a point adjacent the inner edge of the shank portion of the sole, said extension and its projection having flat lower faces and being of the same thickness throughout.

20 In testimony whereof I affix my signature.

CONSTANTINO CARPENTIERI.
